COLLAPSIBLE CABINET

Harry Derman, Laurelton, Long Island, N. Y.

Application December 3, 1938, Serial No. 243,821

12 Claims. (Cl. 312—144)

This invention relates to cabinets of the knock-down or collapsible type and consists primarily of four principal parts, namely a front door frame part, a top part, a bottom part, and a back and side wall part, which parts are adapted to be collapsed one flatly upon the other in the compact packing and shipment thereof; and the object of the invention is to provide a cabinet of the character described wherein the front or door frame part has outwardly bulged frame members at least two of which are grooved on opposed surfaces to form guide channels in which independent door members are slidably mounted to provide doors which are movable to opposite sides of the cabinet in the operation of opening the same and brought into abutting relationship to each other when in closed position; a further object being to provide means constituting parts of the door frame for guiding the free sides of flexible door members onto the side walls of the cabinet and to provide shields preventing said doors from contacting any of the garments suspended in the cabinet as well as to conceal and protect said doors; a further object being to provide means for retaining the shields in close proximity to the inner surfaces of the side walls of the cabinet so as to form substantially V-shaped pockets for the reception of the doors at the inner surfaces of said side walls; and with these and other objects in view, the invention consists in a cabinet of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view of a cabinet made according to my invention showing the doors in an open position.

Fig. 2 is a section substantially on the line 2—2 of Fig. 1.

Fig. 3 is a vertical sectional view through the cabinet as seen in Fig. 1, with parts of the construction broken away.

Fig. 4 is a plan view of one corner portion of a cabinet showing the top wall or cover removed; and,

Fig. 5 is an enlarged sectional detail view substantially on the line 5—5 of Fig. 3.

The cabinet shown in the accompanying drawing to illustrate one method of carrying the

invention into effect comprises four unit parts consisting of a front wall and door frame part 10, a back and side wall part 11, a top wall part 12, and a bottom wall part 13. In the packing and shipment of the cabinet, these parts are detached one with respect to the other, and the part 11 has its back walls 11a and side walls 11b collapsed one upon the other and arranged upon the inner surface of the part 10, while the top and bottom parts 12 and 13 are disposed upon the folded or collapsed part 11, thus forming a relatively thin elongated package of the complete cabinet.

The part 10 consists of a frame composed of vertical side rails 14, joined by outwardly curved top and bottom rails 15, 16, and an intermediate rail 17. The rails 14 are grooved as seen at 14a, note Fig. 2 to receive the forward edges of the side walls 11b of the part 11, whereas the inner corners of these rails intermediate the curved frame pieces 15, and 17, are beveled as seen at 18, which bevels register with grooves 15a, 17a, formed on the lower and upper surfaces respectively of the rails or strips 15, 17. These grooves form guide channels for the upper and lower edges of laterally sliding doors 19, 20, as will be apparent. The doors 19, 20 are composed of single-faced corrugated board forming flexible door members, the corrugations being arranged upon the outer surfaces of the doors to produce a neat and finished appearance when the doors are in closed position.

At the adjacent ends of the doors 19, 20, are reinforcing strips 21, 22, the strip 21 having a tongue 21a, and the strip 22 having a groove 22a to provide an overlapped joint between the strips when they abut centrally of the front of the cabinet in the closed position of said door, thus providing a tight closure for the cabinet. A small pin or nail 23 is arranged centrally of the grooves 15, 17 to form stops limiting the opening movement of each door, and other pins 24 are provided on the rails 15, 17, to engage the strips 21, 22 to limit the opening movement of each door.

Between the curved rails 16, 17, is secured a corrugated bottom closure 25 which seats in grooves on the opposed surfaces of the rails as clearly seen in Fig. 3 of the drawing. This closure is also preferably composed of the single-faced corrugated board to correspond with the arrangement of the corrugations in the door members. In other words, the corrugations are arranged vertically in both instances, thus providing for the free curved flexure thereof. It

will, of course, be apparent that sliding doors similar to the doors 19, 20, may be used as a substitute for the closure 25, if it be desired to gain access to the bottom of the cabinet from the exterior thereof rather than through the door opening controlled by the doors 19, 20.

In the present structure, however, the simpler form of the device is illustrated, and in this construction supplemental vertical reinforcing and 10 guide rails 26 are arranged between the curved rails 15, 17, adjacent the rails 14 and in spaced relation to the latter so as to provide between the rails 26, 14, spaces through which the doors 19, 20 are free to pass. Supported upon the 15 rails 26 are guard or shield strips 27 preferably composed of fibre board and foldable as indicated at 28, note Fig. 4 of the drawing, so that the shields 27 may be collapsed upon the inner surface of the unit part 10 in the packing and shipment of the knock-down cabinet and also extended into the position shown in Fig. 2 to form 20 chambers 29 upon the inner surfaces of the side walls 11b of the cabinet adjacent the front portion thereof for the reception of the free ends of the doors 19 and 20, when the latter are moved 25 into open position.

Supported upon the top of the side walls 11b of the cabinet is a hanger unit 30 which consists of a complete assemblage comprising a 30 hanger rod 31 attached to end links 32, the latter being pivotally supported as at 33 in connection with U-shaped shoes 34 which fit over the upper edges of the walls 11b and also over the upper edge of the shields 27 so as to retain said shields in juxtaposition to the walls 11b as clearly indicated in Figs. 3 and 5 of the drawing. The unit 30 also includes a perforated tube 35 containing suitable insecticide material suitable to protect apparel arranged in the wardrobe 40 against attack by moths.

It will be understood that the shields 27 are of greater length and width than that part of the doors 19, 20, arranged therewithin when the latter are in open position and that these shields 45 in addition to forming the chamber 29 in conjunction with the walls 11b also render the doors invisible at the interior of the cabinet and further prevent any garments arranged in the cabinet from contacting the doors to interfere with 50 the free movement thereof. Each door or the reinforcing rails 21, 22, thereof, are provided with suitable hand grips in the form of recesses 36 in the outer surfaces thereof to facilitate grasping the doors in moving the same into open 55 and closed position.

The top and bottom curved rails 15, 16, are recessed on upper and lower surfaces thereof respectively as at 15b, 16a, as are also the upper and lower ends of the side rails 14 of the frame 60 to receive the forward edge portions 12a, 13a, of the top and bottom parts 12, 13, so as to lie flush therewith producing a neat and finished appearance. It will be understood that the edges 12a, 13a, are cut out to conform with the contour of the strips 15, 16, as is clearly illustrated, for example in Fig. 1 of the drawing, where the relationship of the parts 12, 15, is shown.

The top part 12 is formed from a sheet of fibre board and has at the back and sides downwardly turned flanges 12b to which are secured at the outer surfaces thereof reinforcing wood strips 37 for reinforcing the upper edges of the back and side walls. Corresponding strips 37a are arranged on corresponding flanges 13b of the 70 bottom part 13. The bottom part 13 also prefer-

ably is provided at the corner portions thereof with supporting feet 38 which serve to support the cabinet slightly above the floor or other surface, while at the same time compensating for any slight unevenness that may prevail in a surface. 5

It will also be apparent that other adaptations and uses of the fundamental and basic principles of the structure as herein shown and described can be made within the scope of the appended 10 claims. It will be understood that a closet of the type and kind herein shown and described in addition to providing greater amount of room for the storage chamber within the cabinet also provides a much more sturdy cabinet by reason of the arched construction of the door frame and in addition to these accomplishments, it will appear that a cabinet of more attractive appearance is provided than is commonly found in the conventional rectangular box. 15

It will be understood that the upper and lower ends of the rails 21 and 22 have projecting tongues slidably engaging the grooves 15a, 17a, of the rails 15, 17, to aid in guiding the doors in their sliding movement. It will also be apparent that the door frame unit 10 will be adapted for use in connection with cabinet structures of various kinds and classes; and furthermore my invention is not limited to the specific means herein disclosed for guiding and shielding the 30 inner ends of the doors. 25

It will, of course, be apparent that by making either one of the doors 19, 20, wider and by eliminating the stop pins 23 and one pair of the pins 24, a single door may be used in forming the 35 closure, in which event only one of the shields 27 will be employed and the same will be made sufficiently wide to compensate for the added width of the door. In fact, it is also within the spirit of the invention to employ two closures, 40 but only one of which is movable in controlling the door opening. It will also be apparent that the particular shape or contour of the transverse outwardly bulged members 15, 16 and 17, may be varied, and the grooves formed therein will 45 conform substantially to the contour of the members as well as the closure 25 in the contour defined by said members or the grooves formed therein. 50

Having fully described my invention what I claim as new and desire to secure by Letters Patent, is:

1. A cabinet of the class described comprising top, bottom, back and side walls, the front of the cabinet being open, outwardly bulged transverse frame members at the front of the cabinet, two of said members being spaced apart to form therebetween a door opening at the front of the cabinet, said two members having on opposed 55 surfaces door guiding channels paralleling the outer bulged surfaces of said members, a flexible door closure extending between and slidably engaging the channels of said members and controlling said door opening, said closure being 60 adapted to extend beyond the ends of said channels into the cabinet in the open position thereof, and means inwardly of one end of said channels limiting opening movement of said closure whereby a sufficient portion thereof will remain in said 65 channels to maintain said closure in proper alignment between said members.

2. A cabinet of the class described comprising top, bottom, back and side walls, the front of the cabinet being open, outwardly bulged transverse 70

- frame members at the front of the cabinet, two of said members being spaced apart to form therebetween a door opening at the front of the cabinet, said two members having on opposed surfaces door guiding channels paralleling the outer bulged surfaces of said members, a flexible door closure extending between and slidably engaging the channels of said members and controlling said door opening, said closure being adapted to extend beyond the ends of said channels into the cabinet in the open position thereof, means inwardly of one end of said channels limiting opening movement of said closure whereby a sufficient portion thereof will remain in said channels to maintain said closure in proper alinement between said members, means limiting closing movement of said closure, and means within the cabinet for guiding the closure in the movement thereof into open position in a manner to support the end thereof protruding from said channels substantially flat against inner surfaces of the adjoining side wall of the cabinet, said guiding means concealing the protruding end of said closure.
3. A collapsible cabinet of the class described comprising detachably and collapsibly related unit parts, one comprising a door frame, another back and side walls, a top wall part, and a bottom wall part, said door frame part comprising vertical side rails joined by outwardly bowed top, bottom and intermediate transverse rails, opposed surfaces of the top and intermediate rails having longitudinal grooves, supplemental vertical rails arranged inwardly of the first named side rails and coupled with said top and intermediate rails, said supplemental rails being spaced from the side rails in registering alinement with the grooves in said top and intermediate rails to provide passages therebetween extending into the cabinet adjacent the side walls thereof, flexible doors composed of single-faced corrugated board having reinforced outer ends arranged between the top and intermediate rails and slidably in the grooves thereof and controlling the opening formed between said top and intermediate rails, means at the sides of the cabinet for guiding and shielding the inner ends of said doors in the movement of said doors into open position, said last named means comprising vertically arranged shield plates hingedly supported on the supplemental rails, and means retaining the upper inner corner portions of said shield plates against movement relatively to the side walls of the cabinet.
4. A collapsible cabinet of the class described comprising detachably and collapsibly related unit parts, one comprising a door frame, another back and side walls, a top wall part, and a bottom wall part, said door frame part comprising vertical side rails joined by outwardly bowed top, bottom and intermediate transverse rails, opposed surfaces of the top and intermediate rails having longitudinal grooves, supplemental vertical rails arranged inwardly of the first named side rails and coupled with said top and intermediate rails, said supplemental rails being spaced from the side rails in registering alinement with the grooves in said top and intermediate rails to provide passages therebetween extending into the cabinet adjacent the side walls thereof, flexible doors composed of single-faced corrugated board having reinforced outer ends arranged between the top and intermediate rails and slidably in the grooves thereof and controlling the opening formed between said top and intermediate rails, means at the sides of the cabinet for guiding and shielding the inner ends of said doors in the movement of said doors into open position, said last named means comprising vertically arranged shield plates hingedly supported on the supplemental rails, and means retaining the upper inner corner portions of said shield plates against movement relatively to the side walls of the cabinet.
5. A cabinet of the class described comprising top, bottom, back and side walls, the front of the cabinet having a large door opening giving access to the interior of the cabinet, spaced outwardly bowed rails at the front of the cabinet, flexible doors arranged between and slidably engaging said spaced outwardly bowed rails to form, when the doors are in closed position, an outwardly bowed door closure, adjacent outer edges of the door having longitudinal reinforcing strips abutting and intermeshing centrally of the cabinet when the doors are in closed position, means coupled with said bowed rails and independent of the side walls of the cabinet forming with said side walls door receiving pockets at the side portions of the cabinet into which the inner ends of the doors are free to pass in the movement of the doors into open position, and said means forming shields concealing the inner ends of the doors and guarding the same against engagement with articles supported in the cabinet.
6. A cabinet of the class described comprising top, bottom, back and side walls, the front of the cabinet having a large door opening giving access to the interior of the cabinet, spaced outwardly bowed rails at the front of the cabinet, flexible doors arranged between and slidably engaging said spaced outwardly bowed rails to form, when the doors are in closed position, an outwardly bowed door closure, adjacent outer edges of the doors having longitudinal reinforcing strips abutting and intermeshing centrally of the cabinet when the doors are in closed position, means coupled with said bowed rails and independent of the side walls of the cabinet forming with said side walls door receiving pockets at the side portions of the cabinet into which the inner ends of the doors are free to pass in the movement of the doors into open position, said means forming shields concealing the inner ends of the doors and guarding the same against engagement with articles supported in the cabinet.
7. In a cabinet of the character described, a front door frame unit comprising vertical side rails, outwardly bowed top and bottom rails joining said side rails, an outwardly bowed intermediate rail joining said side rails, supplemental vertical rails arranged inwardly of and in spaced relation to the side rails and extending between the top and intermediate rails, the lower surface of the top rail and the upper surface of the intermediate rail having longitudinal grooves communicating at their ends with the space between the side and supplemental rails, flexible doors

- arranged between the top and intermediate rails and operating in the grooves thereof in the movement thereof into open and closed positions, and means supported on the supplemental rails for guiding and shielding the inner end portions of the doors in the movement of said doors into open position.
8. In a cabinet of the character described, a front door frame unit comprising vertical side rails, outwardly bowed top and bottom rails joining said side rails, an outwardly bowed intermediate rail joining said side rails, supplemental vertical rails arranged inwardly of and in spaced relation to the side rails and extending between the top and intermediate rails, the lower surface of the top rail and the upper surface of the intermediate rail having longitudinal grooves communicating at their ends with the space between the side and supplemental rails, flexible doors arranged between the top and intermediate rails and operating in the grooves thereof in the movement thereof into open and closed positions, means supported on the supplemental rails for guiding and shielding the inner end portions of the doors in the movement of said doors into open position, adjacent outer ends of the doors having longitudinal reinforcing strips slidably engaging the grooved rails, one of said reinforcing strips having a projecting tongue and the other a groove to form a tight closure between the doors when in closed position, and means cooperating with said reinforcing strips limiting the opening and closing movement of each door.
9. A knock-down cabinet of the class described comprising detachably and collapsibly related top, bottom, back and side wall parts and a front door frame unit, said unit comprising vertical side rails and transverse rails, said unit having a large door opening, the transverse rails being convexed outwardly and the forward edges of the top and bottom wall parts being correspondingly formed, a flexible closure for said door opening arranged and laterally movable in said unit and constituting a part thereof, means extending longitudinally of and in parallel relation to the convex outer surface of said transverse rails for guiding said closure in the door frame, said closure being formed from single-faced corrugated board with the corrugations arranged vertically on the closure, and a permanent front closure at the lower portion of said unit and comprising a single-faced corrugated sheet with the corrugations arranged vertically thereon.
10. A cabinet of the class described comprising top, bottom, back and side walls, the front of the cabinet having a large door opening giving access to the interior of the cabinet, spaced outwardly

bowed rails at the front of the cabinet, flexible doors arranged between and slidably engaging said spaced outwardly bowed rails to form, when the doors are in closed position, an outwardly bowed door closure, adjacent outer edges of the door having longitudinal reinforcing strips abutting and intermeshing centrally of the cabinet when the doors are in closed position, movably supported means independent of and arranged adjacent the side walls of the cabinet at opposed sides of the door openings, said means forming in conjunction with the side walls of the cabinet door receiving pockets into which the inner ends of the doors are free to pass in the movement of the doors into open position, and said pockets forming means concealing the inner ends of the doors and guarding the same against engagement with articles supported in the cabinet.

11. In a knock-down cabinet of the class described having collapsibly related side and end wall members, a door frame unit detachable with respect to said collapsibly related members, means forming a door opening in said unit, said means including vertically spaced transverse rails forming top and bottom boundaries of said door opening, said rails being joined by transversely spaced vertical rails, the lower surface of the top rails and the upper surface of the bottom rail bounding said door opening having channels extending longitudinally thereof, transversely movable and independently operable door members arranged in and constituting part of said unit and slidably engaging said channels, adjacent edges of said door members having vertical reinforcing strips, and means limiting the opening movement of said door members to maintain a substantial portion of the door members in said channels and to maintain said strips within said door opening.

12. In a knock-down cabinet of the class described having collapsibly related side and end wall members, a door frame unit detachable with respect to said collapsibly related members, means forming a door opening in said unit, said means including vertically spaced transverse rails forming top and bottom boundaries of said door opening, said rails being joined by transversely spaced vertical rails, the lower surface of the top rail and the upper surface of the bottom rail bounding said door opening having channels extending longitudinally and opening through opposed end portions thereof, transversely slideable door members arranged in said channels and constituting a part of said unit, and portions of said door members in the open position thereof protruding beyond said channel ends.

HARRY DERMAN.
